BELT

Irby F. Gassert and James C. Hoffman, Yoakum, Tex., assignors to Texas Tanning & Manufacturing Company, Yoakum, Tex., a corporation of Texas

Application August 23, 1940, Serial No. 353,959

8 Claims.

(Cl. 241—8)

This invention relates to belts and it is one object of the invention to provide a belt having a buckle and top loops so mounted that they may be removed and others substituted. It will thus be seen that a buckle and set of loops may be transferred from one belt to another or a merchant may carry a stock of extra buckles and loops of various types and qualities and of different values and a customer may select a belt from those in stock and have the merchant apply a selected buckle and set of loops. The customer may also purchase extra buckles and loops to be selectively applied to the belt when so desired and, in addition, metal buckles and loops may be detached from a belt and cleaned and replaced without soiling the belt.

Another object of the invention is to provide a belt including a main strap-like body and auxiliary straps carried thereby, one of the auxiliary straps carrying the buckle and the top loops and having portions firmly but detachably held in engagement with the body in such a manner that while the buckle and the loops will be firmly held in place they may be easily removed when so desired.

Another object of the invention is to provide a belt wherein the auxiliary strap has its buckle-and-loop-engaging portions detachably secured by snap fasteners so located that the loops and the buckle will be held in their proper positions and prevented from moving longitudinally of the belt out of place.

Another object of the invention is to provide a belt wherein a socket for receiving a stud carried by an auxiliary strap also serves as means for securing a rear or inner belt-engaging loop in place.

Another object of the invention is to provide a belt which can be economically manufactured and sold at a reasonable price.

With these and numerous other objects in view, the invention consists in the novel features of construction, combination and arrangement of parts as will be hereinafter referred to and more particularly pointed out in the specification and claims.

The invention is illustrated in the accompanying drawing wherein—

Fig. 1 is a showing of a belt of the improved construction in front elevation.

Fig. 2 is a view looking down upon Figure 1.

Fig. 3 is a sectional view taken longitudinally through Figure 1.

Fig. 4 is a sectional view of one end portion

of the belt showing the auxiliary strap carrying the buckle and the top loops released.

Fig. 5 is a view similar to Figure 4 showing the auxiliary strap in position for removal of the buckle and the top loops therefrom.

Fig. 6 is a perspective view of the buckle and the top loops.

The belt which is indicated in general by the numeral 1 may be formed of leather or any other pliable material desired. This belt is of suitable length and width and its end portions carry auxiliary straps 2 and 3 which are relatively narrow, as shown in Figure 1, and have their inner end portions stitched or otherwise permanently secured against outer faces of the end portions of the belt. The strap 2 is formed with the usual openings 4 to receive the bill 5 of the buckle 6 carried by the strap 3, which strap also carries the top loops 7. These loops fit loosely about the strap 3 and when this strap is released at its outer end, the loops and the buckle may be removed therefrom. The bill of the buckle passes through the slit or elongated opening 8 formed in spaced relation to the outer end thereof. The opening 8 extends longitudinally of the strap to accommodate the eye 9 of the bill 5 and the opening 10 through which the free end of the strap 3 is passed through the strap extends transversely of the belt and is formed with recesses or notches 11 midway its length to accommodate the eye 9.

In order to detachably hold the strap 3 in the secured position shown in Figures 1, 2 and 3, there have been provided snap fasteners consisting of sockets 12, 13 and 14 and companion studs 15, 16 and 17. The sockets are secured through the end portion of the belt carrying the strap 3 with the opening 10 located between sockets 12 and 13 and it should be noted that sockets 13 and 14 have their open ends presented outwardly while socket 12 has its open end presented inwardly, as shown in Figures 4 and 5. It should also be noted that socket 14 not only passes through the belt but also through the outer portion of the rear or inner loop 18 through which the inner over-lapped end portion of the belt passes when the belt is worn and secured about a person's waist. Therefore, this socket will serve as a fastener for the rear loop and hold it in its proper position upon the belt.

When the belts are manufactured the narrow straps 2 and 3 are disposed longitudinally of end portions of the belt 1 and their inner end portions are secured by the stitching 19 and 20. The rear loop 18 is slipped into place about the

belt under strap 3 and secured by socket 14 and the front or top loops 7 are then slipped into place about strap 3 and the bill 5 of buckle 6 passed outwardly through opening 8 of the strap. After the bill has been passed through the opening the free end portion of the strap is passed through the buckle and inwardly through opening 10 of the belt. The studs 16 and 17 are then pressed into the sockets 13 and 14 and since one loop 7 is located between the studs 16 and 17 and the other loop located between stud 17 and the stitched portion of the strap, they will be held in their proper positions at opposite sides of the rear loop 18. Pull is then exerted upon the free end of strap 3 and stud 15 pressed into socket 12 and the buckle will be securely held in place. If a customer does not like the buckle and the loops 7 applied to the belt, the strap 3 may be easily released by exerting pull upon the strap to snap the studs out of the sockets and another buckle and set of loops applied to the strap. A buckle and set of loops made of metal can be removed for cleaning and replaced without the belt becoming soiled during cleaning operation, and if a person purchases several sets of buckles and loops, they may be selectively applied to the belt for use until it is desired to substitute a buckle and set of loops of different color or design.

From the foregoing description of the construction of the invention, the operation thereof and the method of applying the same to use, will be readily understood. It will be seen that we have provided a simple, inexpensive and efficient means for carrying out the objects of the invention and while we have particularly described the elements best adapted to perform the functions set forth, it is obvious that various changes in form, proportion and in the minor details of construction may be resorted to, without departing from the spirit or sacrificing any of the principles of the invention.

Having thus described the invention, what is claimed is:

1. A belt of a length adapting its end portions to overlap when worn, auxiliary straps carried by said belt and extending longitudinally of end portions thereof with their inner end portions secured against the outer face of the belt, a rear loop fitting about one end portion of the belt, snap fastener members spaced from each other longitudinally of the said end portion of the belt with one of the fastener members serving to secure the loop in place about the belt, the said end portion of the belt being formed with an opening spaced from the free end thereof and located between certain of the fastener members, the strap carried by the said end portion of the belt being of a width adapting its free end portion to pass through the opening and formed with an opening for registering with the opening in the belt when the strap is drawn inwardly through the opening, snap fastener members carried by the strap for detachably engaging the snap members of the belt and firmly but detachably securing the strap, the opening of the strap being located between certain of the fastener members thereof, top loops for engaging the other strap fitting loosely about the first strap and held in position at opposite sides of the rear loop when the fastener members are interengaged, and a buckle fitting about the first strap with its bill passing through the opening thereof when the fastener member adjacent the outer end of the strap is interengaged

with the companion fastener member of the belt.

2. A belt of a length adapting it to have end portions overlap when worn, straps extending longitudinally of end portions of the belt and having their inner end portions secured thereto, one end portion of the belt being formed with an opening and the strap carried thereby being of a width adapting it to pass through the opening and formed with an opening to register with the opening of the belt when the outer end of the strap is passed inwardly through the opening of the belt, a rear loop fitting about the belt under the said strap, companion fastener members carried by the belt and the said strap, one of the fastener members carried by the belt also constituting securing means for the rear loop, top loops fitting loosely about the strap and removably held in place thereon when the fastener members are interengaged, and a buckle fitting about the strap with its bill passing through the opening of the strap, said buckle being removably held in place upon the strap when the outer end of the strap is passed through the opening of the belt and fastener members at ends of the strap and the belt are interengaged.

3. A belt of a length adapting it to have end portions overlap when worn, straps extending longitudinally of end portions of the belt and having their inner end portions permanently secured thereto, interengaging fastener members carried by one end portion of the belt and the free portion of the strap carried thereby for releasably holding the free portion of the strap close against the belt, a rear loop fitting about the belt under the said strap, top loops fitting loosely about the strap and removable therefrom when the strap is released, and a buckle removably carried by the strap, the buckle and the top loops being held in place with the top loops located at opposite sides of the rear loop when the fastener members of the strap and the belt are interengaged with each other.

4. A belt of a length adapting it to have end portions overlapped when worn, straps extending longitudinally of end portions of the belt and having their inner end portions fixed to the belt, top loops fitting loosely about one strap and removable therefrom, a buckle removably carried by the said strap, and companion fastener members carried by the belt and the said strap for releasably securing the initially free end portion of the strap close against the belt and holding the buckle and the top loops in place.

5. A belt of a length adapting it to have end portions overlapped when worn, straps extending longitudinally of end portions of the belt and having their inner end portions fixed to the belt, top loops fitting loosely about one strap and removable therefrom, a buckle removably carried by the said strap, and companion fastener members carried by the belt and the said strap for releasably securing the initially free end portion of the strap close against the belt, certain of the fastener members being located between the top loops and between the buckle and one top loop to maintain the top loops and the buckle in predetermined spaced relation to each other longitudinally of the strap, the outer end of the strap being passed inwardly through an opening in the belt and detachably secured against the inner face of the belt by certain of the fastener members.

6. A belt having portions overlapped when

worn, straps extending longitudinally of the said belt portions and having their inner ends secured thereto, one of the said belt portions being formed with an opening spaced from its free outer end, the strap carried by the said belt portion being of a width adapting it to be passed through the opening and being formed with an opening disposed outwardly of said belt portion when the strap is passed through the opening thereof, a buckle fitting about said strap with its bill passing through the opening in the strap, and companion snap fastener members carried by the outer end portions of the said belt portion and the said strap to releasably secure the same in engagement with each other and detachably mount the buckle.

7. A belt having portions overlapped when worn, straps extending longitudinally of the said belt portions and having their inner ends secured thereto, one of the said belt portions being formed with an opening spaced from its free outer end, the strap carried by the said belt por-

tion being of a width adapting it to be passed through the opening, snap fastener members carried by the outer end portions of the said belt portion and the said strap to releasably secure the same in face to face engagement thereof, and a buckle fitting about said strap prior to passage of the strap through the opening and detachably held thereon when the strap is passed through the opening and secured.

5 8. A belt of a length adapting it to have end portions overlapped when worn, straps extending longitudinally of end portions of the belt and having their inner end portions fixed to the belt, a loop carried by one strap, a buckle removably carried by said strap between the loop and the outer end of the strap, and companion fastener members carried by said strap and the belt for releasably securing the initially free end of the strap against the belt and removably holding the buckle in place.
